(57) **CLAIM**

The ornamental design for a guide tool, as shown and described.

DESCRIPTION

FIG. 1 is a front perspective view of a guide tool showing the new design;

FIG. 2 is a back perspective view thereof;

FIG. 3 is a first side view thereof;

FIG. 4 is a second side view thereof;

FIG. 5 is a top view thereof;

FIG. 6 is a bottom view thereof;

FIG. 7 is a front view thereof; and,

FIG. 8 is a back view thereof.

The broken lines in the drawings are for the purpose of illustrating portions of the guide tool that form no part of the claimed design.

1 Claim, 5 Drawing Sheets
